(57) **CLAIM**

The ornamental design for a bottle with surface ornamentation, as shown and described.

DESCRIPTION

FIG. 1 is a front, top perspective view of the first embodiment of a bottle with surface ornamentation in accordance with the invention;

FIG. 2 is a front view of the bottle with surface ornamentation depicted in FIG. 1;

FIG. 3 is a rear view of the bottle with surface ornamentation depicted in FIG. 1;

FIG. 4 is a left view of the bottle with surface ornamentation depicted in FIG. 1;

FIG. 5 is a right view of the bottle with surface ornamentation depicted in FIG. 1;

FIG. 6 is a top view of the bottle with surface ornamentation depicted in FIG. 1;

FIG. 7 is a bottom view of the bottle with surface ornamentation depicted in FIG. 1;

FIG. 8 is a front, top perspective view of the second embodiment of a bottle with surface ornamentation in accordance with the invention.

FIG. 9 is a front view of the bottle with surface ornamentation depicted in FIG. 8;

FIG. 10 is a rear view of the bottle with surface ornamentation depicted in FIG. 8;

FIG. 11 is a left view of the bottle with surface ornamentation depicted in FIG. 8;

FIG. 12 is a right view of the bottle with surface ornamentation depicted in FIG. 8;

FIG. 13 is a top view of the bottle with surface ornamentation depicted in FIG. 8;

FIG. 14 is a bottom view of the bottle with surface ornamentation depicted in FIG. 8;

FIG. 15 is a front, top perspective view of the third embodiment of a bottle with surface ornamentation in accordance with the invention.

FIG. 16 is a front view of the bottle with surface ornamentation depicted in FIG. 15;

FIG. 17 is a rear view of the bottle with surface ornamentation depicted in FIG. 15;

FIG. 18 is a left view of the bottle with surface ornamentation depicted in FIG. 15;

FIG. 19 is a right view of the bottle with surface ornamentation depicted in FIG. 15;

(Continued)

FIG. 20 is a top view of the bottle with surface ornamentation depicted in FIG. 15; and,

FIG. 21 is a bottom view of the bottle with surface ornamentation depicted in FIG. 15.

The broken lines shown illustrate portions of the bottle with surface ornamentation that form no part of the claimed design.
